UNITED STATES PATENT OFFICE

ALBERT W. MOULDER, OF WARREN, OHIO, ASSIGNOR TO GENERAL FIRE EXTINGUISHER COMPANY, OF PROVIDENCE, RHODE ISLAND, A CORPORATION OF DELAWARE

HEATING SYSTEM

Application filed March 25, 1927. Serial No. 178,364.

This invention relates to improvements in heating systems. More especially it relates to means for distributing the flow of a medium, as hot water, through the radiators of such a system equally, or as desired, notwithstanding inequalities in the characteristics and distances of the radiators.

Systems to which the invention applies, such as a hot water system, ordinarily comprise loop arrangements of piping extending from the discharge outlet of the heater to the various radiators and thence back to the inlet of the heater. In small domestic installations the flow of water is usually dependent upon the thermosiphon principle, while in large buildings the circulation is forced by a power pump. In both cases the size of the radiators is determined by the space to be heated, taking into account the various factors affecting loss of heat in the region; and then piping is installed of sufficient size to handle the volume of water that computation determines is necessary for the several radiators. While in theory this should afford a proper performance by each radiator, in practice it is found that certain radiators give off more heat than expected and others fall far short. A careful study of this problem has determined that this variation in expected performance is not due to the resistance of flow within the radiators themselves but is due almost entirely to the conditions of flow through the pipes. That is, apparently the pipes are delivering a considerable quantity of water to one radiator and very little to another. Attempts to correct such conditions by a partial closing of the valves of overfed radiators are unsatisfactory, can afford only temporary correction, at best, and may lead to a worse situation than that originally sought to be improved.

The present invention permits control of the distribution among the several radiators, by fixing the proportionate rate of flow through each radiator. This is done without manipulation of the radiator valves, by providing each local supply pipe with suitable flow characteristics, for example, by inserting a suitable frictional resistance to flow, which resistance is great or small according

as the computed or observed tendency of the particular radiator is to take the heating medium at a rate faster or slower than that at which the other radiators take it. All radiators having once been so regulated or handicapped, each so as to make it in harmony with the remainder of the system, the heating effects of the several radiators will remain in the same proportions to one another as determined at the time of adjustment. The system can then operate as a unit with each radiator distributing its allotted part of the whole heating effect; and a variation in the pressure producing the flow will vary the flow in every radiator.

The invention may be applied in various embodiments, two of which are illustrated in the accompanying drawings. In each the device is applied in the local circuit of the individual radiator, preferably just preceding the inlet valve, and provides a tortuous passage of adjustable length, the length being proportionate to the degree of friction desired for the particular radiator. In one embodiment there is a small vestibular casing into which the feed pipe delivers. The exit from this casing into the radiator is through a succession of short small pipes connected in series by means of reverse elbows. These pipes can be made much smaller than the feed pipe without endangering the continuance of the circulation, although they increase the frictional resistance to flow. The extra length of travel and the sharp bends through the elbows effectively cut down the velocity of flow into the radiator so that the heating effect of the radiator is sensibly altered. To vary the frictional resistance lengths of pipe can be taken out or added, until the desired balance is established between the particular radiator and others.

In the other embodiment the said vestibule is a tube or interior sleeve placed in the section of feed pipe leading to the radiator valve. This sleeve may have a flanged end resting on the radiator valve seat and may itself form a new seat for that valve. A plug, substantially filling this sleeve, except that it has a deep helical groove forms a relatively long passage for the water along the inner

wall of the sleeve, one whose direction of flow is being continuously changed. The frictional resistance afforded by the device can be varied by changing the length of the plug and thereby altering the helical path to be traversed by the water.

In each case the radiator valve can be turned fully open without the radiator taking more than its share of the fluid heating medium. The automatic action of that medium, seeking always the paths of least resistance leads it to the more remote or difficultly accessible radiators, where the resistance inserted for adjustment is less, or is omitted; and the desired uniform distribution of circulation is attained.

It is intended that the patent shall cover by suitable expression in the appended claims, whatever features of patentable novelty exist in the invention disclosed.

In the accompanying drawings:

Figure 1 is an elevation showing a hot water radiator with a casing or vestibule having friction piping which is adjustable in length and in number of reversals, in the inlet course to the radiator;

Figure 2 is an elevation, on large scale and partly in section, of the casing of Figure 1; and

Figure 3 is an elevation, partly in section, showing a different embodiment of the invention.

Referring to the drawings, the radiator 10 receives water through the feed pipe 12 and returns it through the outlet pipe 14. In one of these flow lines, illustrated as being the feed line, an elongated resistance to flow is introduced. This takes the form of a water tight casing or vestibule 18, into which the feed pipe is connected instead of being connected direct to the radiator valve 16, as is customary. Within the casing is the open entrance of a coil of short pipes 20 containing the return elbows 22 and leading through coupling 24 and nipple 25 to the said valve. Water must pass through the successive sections of pipes and elbows before reaching the radiator 10. The frictional resistance encountered by the water during its passage through these pipes, which are preferably somewhat smaller than the feed pipe, cuts down the velocity of the water and thus reduces the rate of flow through the radiator. The capacity of the water passage is not sufficiently changed by these arrangements for friction, to make danger of a blockade or stoppage due to dirt or foreign matter in the water. And no rise in temperature of the water can cause such an expansion of parts as will interfere with the constancy of flow.

To adjust the frictional resistance by reducing it it is only necessary to unscrew one or more lengths of the short pipes; or to add other lengths if the resistance is to be increased.

In the embodiment of Figure 3 no separate casing is needed, but the portion of the feed pipe immediately below the valve assumes the character of a vestibule to the radiator, introducing a frictional water course. This is made by removing the valve stem 16^a and valve clapper 16^b and inserting through the valve seat 16^c into the feed pipe 12, a sleeve 24 which has a terminal out-turned flange 24^a which can seat on the valve seat and itself form a new seat for the valve clapper 16^b. A core 26, fitted within this sleeve, and preferably resting at the bottom against an in-turned flange 24^b has one or more deep helical grooves 26^a throughout its length, and has a lug 26^b at its top end to receive and position a coiled spring 28 which is interposed between said plug and the valve to hold the plug and sleeve within the feed pipe seated respectively at 16^c and 24^b against the flow of water therethrough. The water must flow along the curved path defined by the groove and the inner surface of the sleeve, whereby it both traverses a longer distance, through a smaller pipe, and is also continuously constrained to be changing its direction, until it enters the valve chamber and passes thence into the radiator. Thus an elongated frictional resistance is provided. The valve 16^a can be turned off at will, or be left open wide, without the radiator receiving an undue proportion of the hot water. And the proportional flow received by all radiators in the system can be predetermined, by making adjustment of the length of frictional resistance at the vestibule of each.

I claim:

1. Means for controlling the flow through a radiator having a feed pipe and valve comprising a tube adapted to be inserted through said valve into said pipe; and a core within said tube having a helical groove along its surface; the tube and core being organized to constitute the path of flow, thereby to increase the frictional resistance of this part of the pipe.

2. Means for controlling the flow through a hot water radiator having a feed pipe and valve, comprising a vestibular casing and means therein forming with said casing an elongated and tortuous passage for increasing the frictional resistance to flow, said casing being adapted to be inserted through said valve into said pipe.

Signed at Providence, Rhode Island, this 17th day of March, 1927.

ALBERT W. MOULDER.
